ARTICLE HOLDER

Daniel K. Copell, New York, N. Y.

Application April 2, 1937, Serial No. 134,521

5 Claims. (Cl. 248—315)

The subject matter of this invention is an improved article holder adapted to be readily mounted on a display card and adapted to appropriately support an article in a desired position. The invention has as one object the provision of a serviceable and novel article holder comprising a resilient body having means to initially locate the article inserted and adapted upon rotation of the latter to be distended to firmly grip the located article to prevent accidental shifting thereof in respect to the holder and to the display card. The invention further comprehends the provision of an article holder comprising an expandable and contractible member having means to position and sustain a deformable fastening loop adapted to be readily applied to a support or display card.

The invention further contemplates as an object the provision of an article holder having a substantially disc shaped resilient member which includes an irregularly shaped opening comprising an elongated part having spaced but alined article positioning grooves merging with a relatively expanded part of the opening comprising alined but spaced grooves adapted to receive an article after the latter is first inserted in the positioning grooves and subsequently rotated to be free of the latter whereby the expanded part is elongated to deform the grooves thereof whereby the walls of the latter sustain the rotated article in frictional and in yieldable engagement therewith.

Further objects, advantages and features of the invention will appear from the following detailed description considered in connection with the accompanying drawing in which:

Fig. 1 is a plan view of a display card or support having several article holders according to my invention attached thereto.

Fig. 2 is a sectional view of the article holder taken on the line 2—2 of Fig. 1.

Fig. 3 is a horizontal sectional view of the article holder taken on the line 3—3 of Fig. 1.

Fig. 4 is a perspective view of the article holder illustrated in Figs. 1—3.

Fig. 5 is a plan view of a modified article holder and

Fig. 6 is a sectional view on the line 7—7 of Fig. 5.

The article holder generally designated A comprises a disc 10 and the attached U shaped deformable loop 11. Disc 10 is made of a suitable rubber or other resilient and yieldable material. Loop 11 is made of a suitable bendable but non-resilient strip metal.

As illustrated in Figs. 1—4 inclusive deformable disc 10 is provided with an irregularly shaped opening comprising an expanded part defined by the alined and spaced grooves or slots 12 and an elongated part defined by the alined and spaced grooves as slots 13. Disc 10 is also provided with a suitable slot or striation 14 to permit threading a part of the loop 11 therethrough. To enhance the resiliency of the rim 15 adjacent one of the grooves 12, the rim is provided with a plurality of spaced apertures 16.

Each holder A is adapted to be readily and conveniently attached to the display card on support 17. In this connection arms 18 of a fastening loop 11 which normally straddle the flat sides 15 of its associated substantially annularly shaped member 10 are threaded into spaced openings 19 in the body of the display card 17. The terminals 20 of arms 18 extending in back of the display card are then turned outwardly and against 20 the back surface of the card.

With an annular member 10 fastened to the card, the article, such as a pipe 21, may be conveniently attached thereto. To this end, the bit portion 22 thereof is first inserted into an irregularly shaped opening of a respective disc and in such fashion that the sides 24 of the bit are disposed in the alined positioning or locating grooves 13. Thereafter the bit 22 is rotated approximately ninety degrees. During its rotation relative to the disc 10 sides 24 leave the positioning grooves 13 and enter and interlock with the alined grooves 12 and since bit 22 is of elliptical configuration, rim 15 is distended or deformed, taking the form illustrated in Fig. 2, that is, the formerly elongated part of the irregular opening defined by grooves 13 is contracted and the formerly expanded part of this irregular opening is further expanded and elongated.

Since openings 16 slightly weaken portions of 40 rim 15, this portion is more elastic and readily responds to the rotation of the bit. Having manipulated the pipe in a position where the bit is interlocked with the rim, the deformed and distended rim has a tendency to contract to assume 45 its normal contour shown in Fig. 4, and consequently the bit is frictionally and firmly but removably gripped by the distorted irregularly shaped opening and therefore the pipe is prevented from accidental displacement in respect 50 to the disc and is also prevented from accidental displacement relative to the display card.

With the bit interlocked with the distended locking grooves 12, the bit may be readily removed from the holder by turning it to leave the grip- 55

ping grooves 12 and be disposed in the positioning grooves 13. This operation causes deformed and distended parts of the disc to automatically restore to their original contour. Thereafter the 5 pipe may be readily and slidably disengaged or withdrawn from the positioning grooves 13.

In Figs. 5 and 6 resilient member 10 is provided with an elliptical opening as shown. As in the case of the form according to Figs. 1-4, the 10 article is first positioned in the elongated portion of the central opening thereof. Subsequently the bit is rotated to actuate the walls of the expanded or widest part of the opening to expand or elongate the latter and contract the formerly 15 elongated portion. By this arrangement, the annular rim 15 firmly grasps the bit and prevents accidental displacement thereof. In other aspects the form according to Figs. 5 and 6 is along the lines disclosed in connection with Figs. 1-4 20 inclusive.

While I have described my invention in detail and have referred to several modifications and specific applications thereof, I do not intend that the invention herein disclosed shall be limited to 25 such specific modifications or applications but intend that all matter contained in the above description and shown in the accompanying drawing shall be interpreted as illustrative and not in a limiting sense.

30 I claim:

1. A holder comprising a resilient body having

5 a rim including an opening comprising spaced grooves constituting an elongated part adapted to initially position an article and having spaced grooves constituting a relatively expanded part adapted on rotation of said article relative to 10 said rim to interlock therewith, said rim having a plurality of apertures to enhance the resiliency of said rim adjacent said expanded part.

2. An article holder comprising a resilient body 15 having an elongated opening therein to constitute a rim with said body, said rim having one or more openings to weaken a portion thereof, and a loop carried by said rim and disposed substantially opposite to said weakened portion.

3. A holder comprising a hollow resilient body 20 having a bore and diametrically disposed slots adapted to receive an article and guide displacement of said article relative to said bore, said article upon rotation thereof being disposed out of said slots and adapted to distend said body to permit portions of said bore to clamp against said article.

4. A holder comprising a hollow resilient body having a bore and provided with diametrically disposed slots in communication with said bore. 25

5. A holder comprising a hollow expandable and contractible body having a bore disposed longitudinally of said body and including spaced slots in communication with said bore.

30 DANIEL K. COPELL.
